UNITED STATES PATENT OFFICE.

SHELDON B. EVERITT, OF PLYMOUTH HOLLOW, CONNECTICUT, ASSIGNOR
TO THE THOMAS MANUFACTURING COMPANY, OF SAME PLACE.

IMPROVEMENT IN KNIFE-HANDLES.

Specification forming part of Letters Patent No. 36,255, dated August 19, 1862.

To all whom it may concern:

Be it known that I, SHELDON B. EVERITT, of Plymouth Hollow, in the county of Litchfield and State of Connecticut, have invented a new and useful Improvement in Pocket-Knife Handles; and I do hereby declare that the following is a full, clear, and exact description of the same, reference being had to the accompanying drawings, forming part of this specification, in which—

Figure 1 is a side view of a pocket-knife having its handle constructed according to my invention. Fig. 2 is a longitudinal section of the same. Fig. 3 is an inside view of one half or side of the handle. Fig. 4 is a longitudinal section of the same.

Similar letters of reference indicate corresponding parts in the several figures.

This invention consists in the manufacture of the handles of pen and pocket knives of two shells—one for each side of a handle—stamped or punched out of plates or sheets of silver, German silver, brass, or other sheet metal or alloy, with convex exteriors of any form and design, and having the ends of their concave interiors filled with some metal of more fusible character, or, what is equivalent, with pieces of metal of similar character to that used for the shells, to make those portions of them solid for the reception of the handles.

To enable others skilled in the art to make and use my invention, I will proceed to describe its construction with reference to the drawings.

A A are the two shells forming the sides of the handle, stamped or punched out of sheet metal, with convex exteriors and concave interiors, and a a is the filling of fusible metal or alloy applied within the interiors of the shells at the ends thereof, and extending far enough toward the middle thereof to receive the blades

b b and form flat solid bearings for their sides. A good alloy for this filling may be composed of six pounds tin, one pound lead, ten ounces antimony, two ounces bismuth, and two ounces copper, as, while it possesses the requisite fusibility to prevent injury to the shells, it has the requisite durability to bear the friction of the blades in opening and shutting without material wear. To apply the filling the interior of the shell is first tinned in the proper place for its reception and the alloy in a melted state is dropped into it and then pressed on its surface to make it flat and flush with the edges of the shell. After the filling has set, the shells are drilled for the reception of the pivots c c of the blades and of the pin d, which secures the spring e, which, when riveted, secures the two shells together to form the handle. The blades and spring are applied in the same way as to any other handle.

The handle constructed of the two shells, as above described, can be made at small cost, is very strong, and may be made highly ornamental.

When hard metal is substituted for the soft metal filling a a, it should be stamped out to the required shape and soldered into the shells.

What I claim as my invention, and desire to secure by Letters Patent, is—

The construction of the handle of a pocket-knife of two shells, A A, stamped or punched out of sheet metal or alloy and having the ends of their concave interiors filled with fusible metal or alloy, as shown at a a and herein described, or with an equivalent filling of hard metal.

SHELDON B. EVERITT.
